TRAVERSE MECHANISM OF SPINNING MACHINES

Francis Edward Smallshaw, Hyde, England, assignor to Ashton Brothers & Company Limited, Hyde, England, a British company

Application March 22, 1948, Serial No. 16,263
In Great Britain March 22, 1947

4 Claims. (Cl. 242—43.3)

1

This invention relates to improvements in the traverse mechanism for effecting the chase and building of packages in ring spinning or like frames. As known, the traverse mechanism for dealing with the chase and building is imposed on the motion for actuating the ring rail, and is usually controlled by a heart cam governing the chase traverse and a progressively acting ratchet-wheel mechanism which controls the lift of said rail, the latter mechanism operating a variable sector or toothed quadrant drive or other mechanism for progressively building the cop.

For some yarn packages, and particularly those required for use in the shuttle of an automatic loom, it is customary to start the package with a few coils of yarn closely spaced together at the butt end of the bobbin to form a "bunch" or small reservoir of yarn. This bunch may be formed by manual operation of a lever connected to the traverse mechanism, or by automatic mechanism.

The object of the present invention is to provide a simple and effective means of forming the bunch automatically, whereby once the machine is started up the traverse motion forms the bunch and then proceeds without further attention to build the yarn package in the normal way.

According to the present invention, a traverse mechanism of the kind referred to for imparting the coping or building motion to the ring rails of spinning or like frames is provided wherein the chase is governed by two cams, one of which controls the chase during the initial stages of the building of the package whilst the other controls the chase during the remainder of the building operation, whereby a different chase may be employed for the two stages of building.

In the accompanying drawings—

Fig. 1 is a perspective view of the traverse mechanism constructed in accordance with the invention.

Figs. 2 and 3 are detail views showing the cams fashioned as a single cam unit.

In the preferred embodiment of the invention, a spinning machine and the mechanism for actuating the chase traverse and the build of the packages are constructed in accordance with known practice. In Fig. 1 of the drawings, only so much of the spinning machine is shown as is necessary to understand the construction, arrangement and operation of the improved traverse mechanism. Such traverse mechanism comprises an oscillating framework 10, pivoted on

shaft 11, supported in the side frame 12 and carrying a bowl shaft 13 on which is slidably and rotatably mounted a bowl or rollers follower 14 which works to a cam block mounted on a cam shaft 15 journalled in bearings located in the side frame 12 of the spinning machine. The shaft 15 is driven by worm wheel 17 and worm (not shown) mounted on the drive shaft 18. The cam block comprises two cams, 19 and 20, the cylindrical cam 19 being in the form of a scroll or helical groove 21 cut in the periphery of the cam block and is substantially square in cross-section. The edge cam 20 is a heart-shape cam also having a peripheral groove 22 which is in effect a continuation of the scroll or helical groove 21. Journalled in the oscillating framework 10 is a shaft 23 on which is mounted a drum 24 adapted to receive a chain 25 which extends vertically upwards to a drum 26 mounted on a shaft 27 journalled in the spinning frame 28. Compounded with the drum 26 is a further drum 29 which is connected by chain 30 to chain wheel 31 rotatably mounted at the end of an arm 32 pivotally attached to lever 33 which in turn is pivoted at 34 to a bracket 35 forming part of the spinning frame. The lever 33 has lateral extensions, 36, 37, the outer end of 37 being pivotally connected to the poker 40 attached by its upper end to the ring rail 41, whilst the extension 36 is attached through the intermediary of chain 41a and sprocket 42 to the poker 43 also attached to ring rail 41. It will be obvious that the vertical movement of follower 14 under the action of the cam block will cause the ring rail to move up and down to effect the "chase."

In order to transmit the coping or building motion to the ring rails, the oscillating framework is provided with a mechanism of known construction comprising a ratchet wheel 44 mounted on a shaft 45 and adapted to be rotated one or more teeth-by-ratchet 46 on each downward movement of framework 10. The shaft 45 is connected through worm 47 and worm wheel 48 to the shaft 23 of drum 24, whereby the ring rail due to the rotation of drum 24 will be automatically and intermittently lifted as the spinning process progresses.

The helical groove 21 of scroll cam 19 is of approximately $\frac{1}{8}$ " pitch, and the radial distance of the root of said grooves from the central axis of the shaft 15, and the oscillating framework 10, will of course move up and down to effect the initial or "bunching" stage of the cop building operation in accordance with the variation in such radial distance. The said groove 21 con-

sists of about six spirals, so that the bowl follower 14 will engage same for at least six revolutions of the cam shaft. The minimum radius of the heart-shaped cam 20 is the same as the minimum radius of the scroll cam 19, so that as the bowl follower 14 reaches the end of the groove 21, it is caused to progress easily in to the groove 22 of the heart-shaped cam, where it remains during the remainder of the cop building operation.

The throw of the cam surface formed by the helical groove is such as to provide the short chase on the bobbin when forming the "bunch" at the start of the spinning operation, but does not operate the ratchet-operated copping or 15 cop-building motion. It has been found convenient to arrange the maximum throw of the scroll cam so that it is approximately one-quarter of the maximum throw of the heart cam. The scroll cam illustrated in the drawings provides four cyclic movements of the bowl in the course of one revolution of the cam shaft; hence its shape is substantially square in cross-section, but obviously the number of cyclic movements in any one revolution of the cam shaft can be 20 varied to suit the bunching requirements. The length of the helical groove is made to suit the longest length of yarn required in the bunch and shorter lengths may be made by engaging the bowl with the cam 19 at intermediate positions 30 along the groove 21.

The general shape of the scroll cam may be roughly cylindrical or conical as desired, and the throw of the cam surface in the scroll may be kept the same throughout the scroll, or it may be varied. For example, the shape may be such as to give a chase which starts short, and steadily lengthens in order that successive layers of yarn 35 lock each other and bind the bunch securely in position on the bobbin.

The bowl may be mounted on the main lever in a convenient manner which provides both easy rotation and sliding of the bowl along its shaft. For example, the axis of the bowl shaft may be slightly twisted relative to the axis of the scroll cam, in order to ease the motion of the bowl in the helical groove of the scroll, or alternatively, the bowl may rotate on a spherical boss which is slidably mounted on the bowl shaft so that the axis of rotation of the bowl 50 may be self-adjusting first to the angle of the helix, and then to the track of the heart cam.

The heart cam may be provided with a wall or projecting ridge on the side next to the scroll and having a gap therein at the confluence of the helical groove and the track of the heart cam and the bowl may be loaded by cord and weight or other means so that it bears against the projecting ridge and returns automatically to the far end of the scroll ready for restarting when 55 it is moved out of contact with the heart cam.

In operation, the bowl is set against collar 15 on the cam shaft 15 at the end of the scroll or helix and remote from the heart cam, as shown in chain lines, Fig. 1. The spinning frame is set 60 in motion, and as the cam-shaft rotates, the bowl moves up and down with the changes in radius of the helical groove, and also moves along the bowl shaft by reason of the rotation 65 of the helix. The rise and fall of the bowl influences the oscillating framework 10, and consequently governs the chase during the initial stage of spinning to build the "bunch" at the bottom of each package and the operation continues until the bowl leaves the helical groove 70

and passes or rides on to the periphery of the heart cam, where it remains to govern the chase during the remainder of the winding and building operation and until the yarn package is complete, when the mechanism is reset to make another package.

The scroll cam and bowl may be fitted to existing spinning machines by minor modifications to some of the brackets.

Obviously, the invention is not limited to the details of the embodiment described, and modifications may be made without departing from the scope of the invention. For example, the pitch of the helical groove on the scroll cam may be varied according to requirements, and may be disposed on either side of the heart cam to suit varying constructions of ring frame, and the groove may be either right or left hand.

Further, other means may be provided in lieu of the helical groove to move the bowl axially of the cam governing the chase of the bunch. In this case, said cam is constructed without the helical groove but of the same width as the superseded scroll cam, and having a cam face so shaped as to impart the necessary rise and fall to the main lever to produce the requisite chase. The bowl would be moved axially along its shaft by any suitable or separate mechanism which would also cause the bowl to ride on to the periphery of the heart cam at the end of said axial movement, hold the bowl in contact with the heart cam during the build of the remainder of the package, and return it to its initial position when starting a fresh package.

I declare that what I claim is:

1. A traverse mechanism for imparting cop-building motion to the ring rail of a spinning frame comprising two cams for governing the chase, one said cam being in the form of an annular groove and the other being in the form of a helical groove, a single follower for said cams shaped to enter said grooves, means normally retaining said follower in said annular groove, and means for transferring the follower from one groove to the other.

2. A traverse mechanism according to claim 1, wherein said follower is a roller, and comprising also a spindle on which the roller is rotatably and slidably mounted, said roller lying alongside the two cams, an oscillating frame carrying said spindle, and chain and roller means for converting the oscillations of said frame into chase motion of the ring rail.

3. A traverse mechanism according to claim 1, wherein said annular cam is a heart-shaped cam and imparts to the follower a motion for the main cop-building operation and wherein the helical cam is a block cam and imparts to the follower a motion for the bunching operation, the least diameters of these cams coinciding in one diametrical plane in which plane the follower transfers from one cam to the other.

4. A traverse mechanism for imparting cop-building motion to the ring rail of a spinning frame, comprising an oscillatable open frame, a spindle in said frame parallel with the axis of oscillation and a roller with bevelled periphery slidably and rotatably mounted on said spindle, a rotary cam shaft also parallel with the said axis of oscillation, and a cam secured to said shaft, the major length of said cam being of square section and having a helical V-groove in its periphery, one end of said cam being of heart shape in cross section with an annular V-groove therein, the said grooves having a common least diam-

eter in one diametrical plane and being in open communication in such plane to allow the following to pass from one to the other.
